Alfred J. Dunc

ATTORNEY.

UNITED STATES PATENT OFFICE.

JOHN P. QUIGGAN, OF BROOKLYN, NEW YORK.

PRINTING APPLIANCE.

1,379,936.

Specification of Letters Patent. Patented May 31, 1921.

Application filed February 14, 1918. Serial No. 217,069.

To all whom it may concern:

Be it known that I, JOHN P. QUIGGAN, a citizen of the United States, residing at Brooklyn, in the county of Kings and State 5 of New York, have invented certain new and useful Improvements in Printing Appliances, of which the following is a specification.

The present invention relates generally to 10 printing appliances and is more especially directed to improvements in the construction of the mountings and coöperating clamping devices for printing plates, as described and claimed in Letters Patent of the 15 United States issued to me May 21st, 1912, No. 1,026,767.

The primary object of the present invention is to provide a mounting or base block 20 of a modified construction whereby the printing plate may be expeditiously set and which will accommodate plates of various areas and configurations.

My invention also comprehends a clamping medium to be used in conjunction with 25 the aforesaid mounting or base plates which will be positive in its functioning and is so constructed that it will possess greater durability and may be more expeditiously and 30 economically manufactured than the forms of clamping devices disclosed in my aforesaid Letters Patent.

My invention, among other advantages and objects, also comprehends the provision 35 of means for procuring a more positive coöperation between the mounting or base blocks and the clamping device or medium, so that a printing plate will be firmly held in position and will in effect be an integral part of the mounting or base blocks 40 until released by the proper manipulation of the clamping devices, the latter being so constructed that they may be readily inserted or removed from their seated positions within the base of mounting blocks.

45 Other objects and advantages of my invention will be obvious as I proceed with the following description and I would have it clearly understood that I reserve unto myself all rights to the full range of equivalents to which I am entitled in uses and structure under my invention in its broadest aspect.

I shall now proceed to describe my invention with reference to the accompanying

drawing which illustrates one embodiment 55 of my improved form of mounting or base blocks and their coöperating clamping devices, it being understood that various changes may be made in the specific details of structure without departing from the 60 spirit and scope of my invention.

In the drawings—

Figure 1 is a top plane view of a printing plate, mounting or base, made up of a plurality of block sections showing a plate positioned thereon and the coöperating clamping devices.

Fig. 2 is a plan view similar to Fig. 1, illustrating the manner in which the sections of the blocks may be disposed with relation 70 to each other.

Fig. 3 is a transverse section on the line III—III of Fig. 1.

Fig. 4 is a sectional elevation on the line IV—IV of Fig. 3.

Fig. 5 is an enlarged sectional view of the clamping device taken on the line V—V of Fig. 3; and

Fig. 6 is an enlarged view of the clamping device in perspective.

Referring now to the drawings in which like characters of reference are employed to designate the similar parts throughout the several views, 7 represents the base or mounting which is made up of a plurality of blocks 85 or sections so formed as to register with each other regardless of the position in which they may be disposed, as shown, for instance, in Fig. 2. These blocks or sections are formed from any suitable material and are provided with openings 8 extending therethrough at equally spaced intervals, it being observed that the upper and lower ends of these openings are of the same diameter, the walls thereof tapering slightly 90 from the upper edge in proximity to the lower edge 9 to form an abutment or shoulder 10, the portion of the wall from the shoulder to the lower edge of the opening being straight.

The aforesaid block sections may be assembled in any desired manner and are usually positioned upon a suitable support or bed and clamped or locked together by a frame or other securing means, such as indicated at 11. This, however, forms no part of my invention, and need not, therefore, be described in detail, as obviously any one

skilled in the art to which the present invention appertains, will understand the manner in which these blocks may be maintained in operative position.

5 When the base blocks have been assembled, as previously stated, the printing plate indicated at 12, is then placed in position thereon and the clamping devices placed in position in those openings 8 of the base 10 blocks adjacent to the outer edges of the plate to hold the printing plate in place. Each of these clamping devices, any desired number of which may be employed to properly hold the plate in position, consists of 15 the relatively movable parts or members 14 and 15, the member 14 having an integral lateral extension at the top thereof to provide a jaw 17 for gripping the edge of the plate 12. Both of these parts or members 20 14 and 15 are of non-resilient or non-yieldable material and are so conformed as to produce a wedging action against the tension of the arm 20^a of the spring 20 under the manipulation of the pinion 18 threaded 25 on the stud 16 which may be formed integral with or rigidly secured, as by riveting, to the upper end of the said member 15.

The spring 20, it will be observed, consists of the body portion seated or positioned 30 in the curved or coiled lower end 21 of the member 15, which is movable within the cut-out portion 22 of the enlarged lower end 23 of the member 14, and of the aforesaid arm 20^a and the bifurcated arm 20^b. From the 35 description of the clamping device thus far given, it will be obvious that it possesses great simplicity and may be most economically produced, no means of connection between the coöperating parts being required 40 other than the spring 20.

When the plate 12 has been placed in position on the base formed by the block sections 7, the clamping devices are inserted in the openings adjacent to the edge of the 45 plate and pressed downwardly against the tension of the arm 20^b of the spring 20, until the portions 21^a and 21^b on the opposite edges of the curved or locking portion 21 of the member 15 pass below the shoulder or 50 abutment 10, formed on the interior of the opening 8. With the bifurcated arm 20^b held under tension by the wall of the opening 8 under the conditions just described, it is evident that the arm 20^a of the spring 20 55 will function against the member 14 and hold it in contact with the face of the pinion 18, the outer face of the member 15 bearing against the opposite face of the wall of the opening 8. Therefore, when the pinion 18 60 is rotated by means of a rack or other tool (not shown) adapted for engagement with the teeth of the pinion, the said pinion will travel along the threaded stud 16 and advance the jaw 17 toward the edge of the 65 printing plate 12, the member 14 being aper-

tured at 14^a so that the stud is freely movable therethrough. Simultaneously with the movement of the jaw 17 toward the edge of the printing plate by the functioning of the pinion 18, the locking element 21 at the 70 lower end or extremity of the member 15 is moved toward the wall of the opening so that its upper edge engages the under side of the shoulder 10. Therefore when the jaw has been advanced or moved to clamping 75 position—that is to a complete and positive contact with the edge of the plate, it will not only be secured against longitudinal movement by the engagement of the locking element 21 with the under side of the contiguous shoulder 10, but be manifest that the clamp will be wedged and positively held in position against other movement by the pressure exerted by the spring 20 and its co-acting arms 20^a and 20^b and the 80 counter pressure of the jaw carrying member 14 by its coöperation with the member 15 through the medium of the pinion 18. To release the printing plate from engagement with the clamping device and withdraw the 85 latter from its position within the opening 8, the pinion is rotated in the direction opposite to that in which it is moved to perform its clamping function. This releases the pressure exerted by the spring 20 and 90 the counter pressure of the members 14 and 15 so that the upper edge of the clamping device may be tilted forwardly toward the arm 20^b of the spring 20 to release the portions 21^a and 21^b from engagement with the 95 shoulder 10 and permit the withdrawal of the clamping device in a longitudinal direction.

From the foregoing description it will be manifest that the form of clamping device 105 which I have devised and the coöperating blocks or sections for forming the base for supporting the printing plate possess a high degree of simplicity and may be manufactured and assembled with great facility and 110 economy. At the same time the clamping device is so constructed that it positively grips the printing plate and simultaneously wedges or locks itself in position in the opening in the block so as to hold the printing 115 plate in position as if it were virtually an integral part of the supporting base or bed formed by the block sections.

Having thus described my invention what I claim as new and desire to secure by Letters Patent of the United States, is;

1. In a printing appliance, the combination of a base block having a series of annular openings therein formed with shoulders adjacent to their lower ends, and a 125 printing plate adapted to be positioned thereon, of means for positively fastening the printing plate to said block, said means comprising a clamping device formed for location within an opening in said base block 130

and provided with a plate-engaging jaw at its upper extremity, the lower extremity of said device having a surface adapted to engage with said shoulder, and means carried by said device and operable to function said jaw whereby the plate will be immovably held on said base.

2. In a printing appliance, the combination of a base block having a series of annular openings therein, enlarged adjacent to their lower ends to provide an inwardly directed shoulder, and a printing plate adapted to be positioned on said block, of means for positively fastening the printing plate to said block, said means comprising a clamping device formed of two members, one of said members being provided with a plate-gripping jaw at its upper extremity, means formed at the lower extremity of the other of said members for engagement with said shoulder, said members being yieldably connected, and means carried by said latter member and capable of actuation to simultaneously function said jaw and hold said shoulder-engaging element in engagement with said shoulder whereby said plate will be rigidly fastened to said block.

3. In a printing appliance, the combination with a base block having annular openings formed therein at equally spaced intervals, said openings being provided with shoulders on their inner surface adjacent to the lower ends thereof, and a printing plate positioned on said block, of a clamping device adapted to be inserted in one of said openings and engage said plate to rigidly clamp said plate to said block, said device comprising a pair of relatively movable members formed of non-yielding material, one of said members being formed with a plate-gripping jaw at its upper extremity, means for engaging the shoulder of the opening carried at the extremity of the other of said members, means for yieldingly connecting said members, and means capable of actuation to simultaneously function said

jaw and move said shoulder-engaging element into engagement with said shoulder whereby the plate clamping device and base block will be rendered relatively immovable. 50

4. A clamping device for fastening printing plates to base blocks provided with annular openings, comprising a pair of members formed of non-yielding material, a yieldable connection between said members, 55 one of said members being provided with a plate-gripping jaw while the other of said members is formed with a surface adapted for locking engagement with the inner wall of the opening in the base block, and means 60 operable to simultaneously function said jaw and said locking element.

5. In a printing appliance, the combination of a base block having a series of annular openings therein, enlarged adjacent to 65 their lower ends to provide an inwardly directed shoulder, and a printing plate adapted to be positioned on said block, of means for positively fastening the printing plate to said block, said means comprising 70 a clamping device formed of two members, one of said members being provided with a plate-gripping jaw at its upper extremity, means formed at the lower extremity of the other of said members for engagement with 75 said shoulder, said members being yieldably connected, and means carried by said latter member and capable of actuation to move said jaw into engagement with said plate to lock the same in position upon said block. 80

6. A clamping device for fastening printing plates to perforated base blocks, comprising a pair of members formed of non-yielding material, a yieldable connection between said members, one of said members 85 being provided with a plate engaging jaw and the other of said members having a surface formed for locking engagement with the inner surface of an opening in said block, and means for moving said jaw into 90 functioning position.

JOHN P. QUIGGAN.
